RETRACTABLE LANDING GEAR

René Lucien Lévy, Montrouge, France, assignor
to Société d'Inventions Aéronautiques et
Mécaniques S. I. A. M., Fribourg, Switzerland

Application January 9, 1936, Serial No. 58,396
In France January 12, 1935

1 Claim. (Cl. 244—102)

This invention relates to means for retracting the landing gear of aeroplanes, or the floats of hydroplanes, the embodiment of which considerably simplifies known constructions by rendering 5 superfluous the usual multiple lifting-control members and the special locking means required when the parts are in the lowered position.

The characteristic of the present invention consists in compelling a material point on the mobile member and situated between the wheel or its equivalent and the hinge of the supporting leg or its equivalent to remain always at an invariable distance from a definite point on the aeroplane, during the whole time the system is passing from 10 the lowered position to the retracted position, and vice versa.

This guidance can be effected by the provision of a single directing bar of constant length, pivoted at said definite and material points. The 20 definite pivotal point of the direction bar is determined as a function of the relative dimensions of the members of the supporting leg and the retracted position of the wheel, so that, on the wheel being displaced by any means whatsoever, 25 said wheel passes automatically from the lowered to the retracted position, and vice versa, while the locking of the wheel in the lowered position—whereby by means of the lifting member itself, or by any other means—is sufficient to make the entire system rigid.

In the accompanying drawings:

Figures 1 to 3 are diagrammatic views of known constructions of retracting means for aeroplane landing gear;

Figure 4 is a side elevation, and

Fig. 5 is a front elevation of a retractable landing gear in accordance with the present invention;

Figs. 6 and 7 are views corresponding with Figs. 4 and 5 of a modification of the invention.

Referring to the drawings in detail: In the case of machines with two or more engines, the general practice for retracting the landing gear is to employ systems of the type represented in Figure 1, in which the unit, formed by the wheel 1, and supporting fork or leg 2, turns on a pivotal axis 3 so as to raise the wheel to a position 4, in which it is housed in the wing 5, or in the nacelle of the engine.

This solution often has the inconvenience of 50 bringing the raised wheel into a position which is too far rearward in relation to the axis 3, whereas it is desirable—for example, in order to avoid or lessen changes set up in the centre of gravity of the aeroplane by the retraction of the wheel—

to house the wheel in a position 4a, as near as possible to the axis 3 about which it is raised.

This retracted position 4a of the wheel, in the immediate vicinity of said axis, also has the advantage of lodging the wheel between the longitudinal booms (not shown) of the wing or, more generally, at the point most compatible with the type of construction employed for the aeroplane.

It is also known—in order to enable the wheel or its equivalent to be raised as close to the axis 10 3 as possible—to provide a hinge 6, see Figure 2, on the supporting leg 2, in such a manner that the said leg, or its equivalent, can fold, as indicated in Figure 3, so as to bring the wheel into the most suitable position.

These systems, however, leave open two degrees of freedom to the lifting movement of the wheel 1, and consequently allow it to move, not along one curve, but through a series of curves, so that, in order that the raising can proceed along a definite path, it is necessary to provide a plurality 20 of control members, resulting in complicated, heavy and expensive construction.

Moreover, when the landing gear is in the lowered position, it is necessary, in these systems, to 25 ensure rigidity at the hinge of the supporting leg, by auxiliary means, such as hydraulic, mechanical or other locking devices.

Referring to Figures 4 and 5, wherein the present invention is illustrated, a wheel 1 is carried 30 by a leg 2, composed of two members hinged together at a point 6. The lower member, below the hinge 6, consists, for example, of a shock absorber, whilst the upper member is adapted to turn on a fixed pivot 3, the whole of this arrangement being, as already mentioned, known per se.

According to the invention, a material point 7 on the member 2 is compelled to remain at a constant distance from a definite point 8 on the aeroplane, for example, by means of a directing 40 bar 9. Under these conditions the deformation of the system, so as to bring the wheel from the lowered position 1 to the raised position 1b, proceeds in a perfectly definite manner, the position assumed by the various members, on being 45 raised, being shown, in Figure 4, by broken lines and the reference numerals of said members being differentiated by the index character b, the hinge 6 moving to the position 6b.

Moreover, this deformation may be effected by 50 a single control effort, suitably directed and applied at a point on the wheel 1 or the supporting leg 2, for example by means of a jack 10, which is pivoted to the aeroplane at 11 and the piston 55

of which is attached to the lower member of the leg 2 at 12.

In this example, the jack 10, which effects the raising operation, also serves to lock the system 5 when the parts are in the lowered position.

In the embodiment of the invention shown in Figures 6 and 7, the above described combination of the members is again present, especially the directing bar 9 connecting a material point 10 7 on the supporting leg with a definite point 8 on the aeroplane.

In this example, the lifting jack 13 which, on the one hand, is pivoted at a fixed point 14, acts, on the other hand, on a hinge 15 provided on 15 an auxiliary leg 16—16, instead of acting directly on the supporting leg 2.

As in the preceding example, the action of the lifting jack 13 is sufficient in itself—by opening the hinge 15—to bring the deformable system 20 progressively into the position in which, by the action of the bar 9, the wheel is completely retracted, viz. 1b.

As before, the reference numerals of the various members of the system, when in the raised 25 position, are distinguished by the index character

b. Finally, in this case also, the presence of the lifting jack 13 is sufficient, by locking the hinge 15 in the lowered position of the gear, to ensure the rigidity of the system in that position.

In the foregoing description, the term "supporting leg" should be understood as comprising any device for connecting the wheel, or its equivalent, with the axis about which the lifting takes place, and being constituted by an elastic device, fork, or any other device. 5 10

What I claim as my invention and desire to secure by Letters Patent is:—

Retractable landing gear for aeroplanes comprising, for a wheel, a supporting frame, a fixed pivot pin for this frame, a knee joint at one point 15 of this frame, a control bar pivoting about a fixed point of the aeroplane and pivoted, on the other hand, on the supporting frame at a point situated between the wheel and the point of articulation of said frame, an auxiliary leg pivoted, on 20 the one hand, on the aeroplane and, on the other hand, on the supporting frame, and a lifting device pivoted, on the one hand, on the aeroplane and, on the other hand, on said auxiliary leg. 25
